W. READING.

Corn Sheller.

No. 9,120.

Patented July 13, 1852,

UNITED STATES PATENT OFFICE.

WM. READING, OF WASHINGTON, DISTRICT OF COLUMBIA.

CORN-SHELLER.

Specification of Letters Patent No. 9,120, dated July 13, 1852.

To all whom it may concern:

Be it known that I, WILLIAM READING, of the city of Washington and District of Columbia, have invented a new and Improved 5 Corn-Shell; and I do hereby declare that the following is a full and exact description thereof, reference being had to the accompanying drawings, making part of this specification, in which—

10 Figure 1, is an end view of my improved corn sheller, Fig. 2, a longitudinal vertical section of the hollow case and frame, in the line α , of Fig. 1, and a side elevation of the other parts of the machine, and Fig. 3, a 15 transverse section, in the line γ , of Fig. 2.

Like parts are designated by like letters in all the figures.

I construct my improved corn-sheller in the following manner:—I employ a hollow 20 cylindrical case A, of suitable dimensions, (say about 4 feet long, and 16 inches in diameter), and place it nearly horizontally in its frame, or so that the end, into which the corn is to be fed, shall be some 2 inches 25 higher than the other end. Within said cylindrical case I place a cylinder B, extending its entire length, and of such diameter as to leave a space of about 4 inches everywhere between its periphery and the 30 case A. On the periphery of said cylinder I place a set of parallel ridges b , b , &c., or rows of teeth— $\frac{1}{2}$ inch high or thereabout—winding around it about $\frac{1}{4}$ its circumference in its entire length. At the bottom of the 35 case A, I place a small cylinder C, of the same length, and so situated that its upper side shall just reach through the lower side of the case A, where an aperture h , is made to admit it, of sufficient size only to allow 40 shelled corn to pass out by the small cylinder C, and not the cobs. Two or more ridges c , c , are placed on the periphery of said cylinder C, parallel with its axis and about $\frac{1}{2}$ inch in height. The cylinder B, 45 is revolved in the direction indicated by the arrow Fig. 3, or so that the spiral ridges b , b , &c., shall gradually drive the ears and cobs to the discharging aperture g , of the case A. The speed of the cylinder B, should not 50 be so great as to break the grains, but as high as may be without producing such result. I find by experiment that 800 revolutions per minute make a proper speed for a cylinder 8 inches in diameter. The cylinder C, is driven by the cylinder B, and so as to turn in the direction the reverse of that

of the cylinder B, as indicated by arrows in Fig. 3. The object of this is, that the cylinder C, may not retard but accelerate the motion given to the corn by the cylinder B. 60 On the descending side of the small cylinder C, the opening h , in the case A, should be only large enough to allow the shelled corn to pass out, otherwise the cobs would be driven into the space and clog there. But 65 on the ascending side of said cylinder C, the space may be considerably larger, provided it does not allow the cobs to drop through, because the upward action of the cylinder C, and of its ridges c , c , would prevent 70 the cobs clogging therein.

a , is the hopper when the ears of corn are inserted; g , the aperture for discharging the cobs.

The operation of my sheller is as follows. 75 viz—The unshelled ears being thrown in at the hopper a , are kept in motion by the revolving cylinder B, causing the ears to strike together, beat against the sides and top of the case A, and especially against the cobs, 80 which soon accumulate at or near the bottom; the space around the revolving cylinder B, being left large for that purpose, and to allow free play to the ears; and this is an important and distinguishing feature 85 of my invention. At the same time, the spiral arrangement of the ridges or teeth b , b , &c., gradually move the ears and cobs to the other end of the machine, and finally out through the opening g , when the ears 90 will be found to be completely shelled. The small cylinder C, with its ridges c , c , revolving at the same time, clears the shelled corn from the case A, leaving the cobs at the bottom, and ascending side of the cylinder B, which form an elastic bed of sufficient firmness to render the shelling complete without the use of any rest, which always requires a great addition of power. Thus a large quantity of ears is kept 95 constantly in all parts of the sheller, and continually in motion, by which they are more quickly and effectually shelled, with much less expense of power than by any other sheller known to the subscriber. 100

Having thus fully described my improved corn sheller, what I claim therein as new and desire to secure by Letters Patent, is—

The within described combination of a toothed or flanged cylinder with an inclosing cylindrical casing of such proportions respectively, and so arranged the one within 110

the other, as to leave an amount of space between the two which will cause the cobs and ears to clog and accumulate therein, during their passage through the same, and form 5 an elastic self adjusting bed for the spirally arranged teeth or flanches of the shelling cylinder to act in concert with, in place of

the stationary bar or rest which is employed in all other cylindrical corn shellers.

WILLIAM READING.
